(57) **CLAIM**

The ornamental design for a lamp, as shown and described.

DESCRIPTION

FIG. 1 is a left side view of a first embodiment of a lamp; FIG. 2 is a top plan view thereof;

FIG. 3 is a perspective view of top, rear, and right side thereof;

FIG. 4 is another perspective view of bottom, front, and right side thereof;

FIG. 5 is a front view thereof, the rear view being a mirror image thereof;

FIG. 6 is a right side view thereof;

FIG. 7 is a left side view of a second embodiment of a lamp;

FIG. 8 is a top plan view thereof;

FIG. 9 is a perspective view of top, rear, and right side thereof;

FIG. 10 is another perspective view of bottom, front, and right side thereof;

FIG. 11 is a front view thereof, the rear view being a mirror image thereof; and,

FIG. 12 is a right side view thereof.

The broken lines shown and the areas within the broken lines represent unclaimed subject matter and form no part of the claimed design.

1 Claim, 12 Drawing Sheets
